RIFLE MOUNTED GRENADE CATAFULT

Billy B. Scott, Independence, Mo.

Application October 20, 1953, Serial No. 387,147

1 Claim. (Cl. 124—7)

This invention relates to the class of weapons, and more particularly to a novel grenade catapult adapted to be used in combination with a rifle or like small arms.

The primary object of this invention resides in the provision of a catapult for grenades that is capable of being readily and easily attached to various existing types of rifles and other small arms in a manner so as to enable the weapon to be used in conjunction with a loaded rifle so that optionally a bullet may be propelled or a grenade may be thrown at the target.

One of the features of the construction of this invention resides in the provision of means for adjusting the ultimate range that the grenade will be thrown. Other objects and features of the invention reside in the provision of means for automatically removing the release pin of the grenade. The grenade catapult is so positioned that it will not hinder the line of sight utilizing the conventional mechanical sights of the rifle so that simultaneously or optionally, a grenade may be thrown at the target by aiming the rifle and a bullet may likewise be projected at such target.

Still further objects and features of this invention reside in the provision of a grenade catapult that is strong and durable, simple in construction and manufacture, capable of being installed on most makes and models of small arms, and which is highly effective in use.

These, together with the various ancillary objects and features of the invention which will become apparent as the following description proceeds, are attained by this grenade catapult, a preferred embodiment of which has been illustrated in the accompanying drawings, by way of example only, wherein:

Figure 1 is a top plan view illustrating the manner in which the grenade catapult is operatively installed on a rifle;

Figure 2 is an enlarged vertical sectional view as taken along the plane of line 2—2 of Figure 1 and illustrating in phantom lines the position of the catapult after release;

Figure 3 is an enlarged horizontal sectional view as taken along the plane of line 3—3 in Figure 2 illustrating the resilient means used for actuating the lever of the catapult;

Figure 4 is a vertical sectional view as taken along the plane of line 4—4 in Figure 3 and illustrating the manner in which the catapult is secured to the rifle;

Figure 5 is a sectional detail view in an enlarged scale as taken along the plane of line 5—5 of Figure 1 and illustrating the trigger means for releasing the catapult;

Figure 6 is a sectional detail view as taken along the plane of line 6—6 in Figure 3 and illustrating the means for presetting the range of the device; and

Figure 7 is a sectional view as taken along the plane of line 7—7 in Figure 5, further illustrating the trigger means.

With continuing reference to the accompanying drawings wherein like reference numerals designate similar parts throughout the various views, reference numeral 10 generally designates a rifle of conventional construction

2

provided with a barrel 12 secured on a stock 14 and having mechanical sights such as indicated at 16 and 18. The grenade catapult comprising the present invention is indicated generally by the reference numeral 20 and is adapted to be mounted upon the rifle 10.

Incorporated in the grenade catapult 20 are a pair of brackets 22 and 24 of the configuration as is best seen in Figure 4 which are adapted to be clampingly secured about the stock 14 and barrel 12 and held in place by a suitable threaded fastener as at 26. The fastener 26 lockingly holds the lower portion of the brackets 22 and 24 in place on the rifle 10, the upper portions thereof being held in position by means of a shaft 28 which is journaled in the brackets 22 and 24.

The shaft 28 is provided with a knurled enlarged head 30 and has a pawl 32 attached thereto. The other end of the shaft 28 is of substantially reduced diameter, as at 34, and is threaded as at 36 for reception of a lock nut 38 holding a collar 40 thereon. A coil spring 42 is positioned concentrically with the substantially reduced portion 34 and biases the collar 40 and the side portion 44 of the bracket 22 to hold the catapult 20 on the rifle 10. The side portion 46 of the bracket 24 is provided with a plurality of outwardly struck detents 48 which are adapted to be selectively engaged by the pawl 32.

The shaft 28 has one end of a comparatively strong spring 50 attached thereto, the other end of the spring, as at 52, engaging and being positioned beneath the lever 54, the ears 56 of which are rotatably mounted on the shaft 28. The free end of the lever 54 is provided with a grenade receiving receptacle 58 of concave, substantially dish-shape.

Attached to the receptacle 58 is a substantially L-shaped sear 60 which is adapted to be lockingly held in a lower position by means of a spring 61 pressed trigger member 62 slidably mounted on a projecting portion 64 secured to the stock 14 of the rifle 10. Hence, upon actuation of the trigger member 62, the horizontally extending portion 66 of the L-shaped sear 60 is released, thereby permitting the spring 50 to cause the lever 54 to move from the position as is shown in Figure 2 to the position as shown by the phantom lines in Figure 2. The movement of the lever 54 is limited by the stop members 68 and 70 attached to the side portions 44 and 46. In order to remove the release pin 72 of a grenade 74 positioned within the receptacle 58, there is provided a latch member 75 which is attached to the pin 72 and also to an inverted L-shaped member 76 having a V-shaped recess 78 therein into which the latch 75 can be positioned. Hence, upon release of the trigger 62, the latch 75 will cause the pin 72 to be removed from the grenade.

It is to be noted that adjacent each of the detents 48 there is provided suitable indicia 80 indicative of the amount of tensioning of the spring 50. As can be readily understood, the amount of tensioning of the spring 50 can be controlled by rotating the shaft 28. This can be accomplished by pulling the head 30 outwardly so as to compress the spring 42 and then rotating the shaft 28 to the desired position, at which time the head 30 may be then pushed inwardly and interlocked with the selected detent 48. The range is, of course, predetermined by the amount of energy stored in the spring 50. Furthermore, it is within the concept of this invention to provide an adequate tool for increasing the leverage. It is to be recognized that the spring 50 is tensioned before the lever 54 is placed in a lowered condition.

In utilizing this device, it is merely necessary to aim the grenade 74 by aiming the rifle. The range is, of course, predetermined by the preset range on the indicia or scale 80, and of course, can be increased or decreased by elevating or depressing the rifle 10.

Since from the foregoing, the construction and ad-

vantages of this grenade catapult are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications and equivalents may be readily resorted to.

What is claimed as new is as follows:

A grenade catapult for use in combination with a rifle comprising a pair of brackets clampingly secured about the rifle and having upwardly extending side portions, a shaft journaled in said side portions and having one end of a spring secured thereto, means for lockingly holding said shaft in a selected position attached to one of said side portions, a lever rotatably mounted on said shaft, a grenade receiving receptacle on the free end of said lever, the other end of said spring engaging said lever, trigger means for releasably holding said lever in a cocked position with said spring under tension, and means attached to said rifle for disengaging the pin of a grenade when said trigger means has released said lever, said brackets having stops thereon for limiting the movement of said lever after release by said trigger means, said

means for lockingly holding said shaft in a selected position comprising a headed knob attached to said shaft, a pawl attached to said shaft, and a plurality of detents attached to said one of said side portions, said pawl selectively engaging one of said detents, said shaft having a portion of reduced diameter extending through the other of said side portions, a collar on said portion of reduced diameter, and a coil spring disposed concentric with the portion of reduced diameter biasing said collar and said other of said side portions apart whereby the pawl is urged into engagement with said one of said side portions and the pair of brackets is held on the rifle.
